UNITED STATES PATENT OFFICE.

ALBERT FROMMANN AND PHILIPP ENCK, OF CHICAGO, ILLINOIS.

CAR-COUPING.

SPECIFICATION forming part of Letters Patent No. 591,919, dated October 19, 1897.

Application filed October 19, 1896. Serial No. 609,340. (No model.)

To all whom it may concern:

Be it known that we, ALBERT FROMMANN and PHILIPP ENCK, residing at Chicago, in the county of Cook and State of Illinois, have 5 invented certain new and useful Improvements in Car-Couplers, of which the following is a specification.

Our invention relates to a car-coupler having certain novel features of construction by 10 which we obtain a very positive coupling or connecting device for railroad or other cars and which permits the operation of coupling or uncoupling to be performed with comparative ease and safety.

15 The details of construction of the coupler are illustrated in the accompanying drawings and will hereinafter be particularly described.

In the drawings, Figure 1 is a perspective view of the end portions of two cars having 20 a coupler embodying our improvements. Fig. 2 is a plan view, enlarged, of the coupler, showing the parts as when connected together, the surrounding portions being removed to more clearly show details. Fig. 3 25 is a sectional elevation of same with one of the car-bodies dropped below the level of the other, and Fig. 4 is a modification showing the coupler in sectional elevation with the 30 parts as in position during operation of uncoupling.

The present invention, broadly or collectively speaking, consists, essentially, of two members, one an arrow-headed or cuneiform 35 draw-head, and the other a double-hooked head which engages projections on the first member when the heads are coupled. These members, which are classified each as whole 40 as X and Y, respectively, are located on opposite ends of cars, for instance, as shown in Figs. 1 and 3, A A there representing freight-car bodies. a refers to the general framework, and a' a² are the end sills or plates. While we have only shown the coupler as applied to a 45 freight-car, it is readily to be perceived without further illustration, or with but minor changes, that the invention may be used on any well-known type of car for passengers, freight, street-railroads, &c.

50 The features in detail of the members X and Y and adjacent parts are as follows:

The draw-head X when viewed from above

resembles an arrow-head, and consists of a pointed wedge x, having preferably curved vertical sides x' when the head is in a horizontal position. The rear of the wedge is of greater width than the stem or neck x², so as to provide shoulders or outwardly-projecting hooks x³, which serve to engage opposite hooks on Y. The head X is hinged or attached pivotally to the draw-bar B, and this is preferably accomplished by using a leaf or tongue b, pivoted or jointed at b' and b². The head X moves vertically when operated by suitable means and may be turned up. 65 We have shown for this purpose a rod C, having handles c and an arm c', which is provided with a tie, such as a chain c², attached to the outer end of the head X. By operating the handle c the head X may be turned 70 up for uncoupling or may be placed in such position as desired.

Y is the double-hooked draw-head, which consists of two long arms or bars y y. The inner portions of these arms serve the purpose of draw-bars and are pivotally attached to the car or a part thereof at y'. The arms of Y are curved or bent outward at y² y² and have inturned or inwardly-projecting hooks or catches y³ y³ near outer extremities. These 80 hooks have curved or outwardly-receding sides y⁴ y⁴. A space Z is formed between the two arms of Y.

D D are transverse springs bearing against the arms y y, and d is a rod or tie with nuts 85 d' d' for retaining springs in position.

The arms y y are permitted to open laterally with the hooks—that is, they are pivoted so as to move horizontally apart against pressure of the springs D D, which tend to bring 90 the arms together.

E refers as a whole to a keeper for preventing the disengagement of the heads X and Y when coupled by either part slipping up or down from the other. This keeper has two 95 horizontal movable fingers e, one above and below the head Y, the said fingers being attached or mounted on a short shaft or spindle e', which passes through and has a bearing in a part of the head Y, as indicated in Figs. 100 2 and 3. A short arm e² is attached to the keeper near the pivotal point of fingers, and connected to the arm e² are two transverse rods e³, mounted on the end of car. By op-

erating either of the rods e^3 the fingers e may be turned in or out of the way for retaining engagement of or allowing disengagement of the coupling-heads.

5 F F are buffers placed centrally beneath the coupler. These buffers are mounted on heavy metal brackets ff , secured to the framework of cars. These brackets have openings or slots $f' f'$, which serve as housings or supports for the draw-bar portions of the coupler. While the buffers constructed or arranged as shown are a valuable adjunct to the coupler, serving to lessen shock or prevent injury during the operation of coupling, they are not absolutely essential to the invention.

10 All the parts of the coupling-heads are preferably made of malleable iron or of soft steel, with ample pins of steel for the joints.

The operation of the coupler is as follows:

20 When it is desired to couple two cars, they are shoved or placed together and the coupling action of the members X and Y occurs automatically. The wedge portion x spreads the hook extremities $y^3 y^3$ outward and laterally, thus permitting the wedge to enter the space Z, when the action of the springs D D will bring the hooks $y^3 y^3$ into engagement with the projections $x^3 x^3$, thus locking X and Y together. Should the cars not be of the same level, the outer portion of X may be raised or lowered by the lever device C c c', and then secured by the keeper E.

25 To uncouple X and Y, the keeper E is turned and the part X is raised or turned out of engagement with the hooks of Y, when the cars may be pulled apart.

30 By having the hooks $y^3 y^3$ curved outwardly sufficiently the cars may be readily coupled on curves.

35 40 The keeper E is not absolutely essential for carrying out the main features of the invention and may be dispensed with.

45 Where a platform will not admit of the head X being turned up, the arms of Y may be opened to admit uncoupling by using a toggle-joint lever attachment, as indicated by the dotted lines at G G in Fig. 2.

50 To meet the emergency, when it is desired to couple a car having an ordinary head of the link type to one having the head X, we preferably make the head X with a slot or opening H, adapted to receive the end of a

link, and a vertical perforation or hole h for a coupling-pin.

It will thus be seen that our invention provides a very durable, simple, and effective device for the purposes for which it is intended and which may be operated with safety and with very little skill.

60 What we claim is—

1. In a car-coupler, an arrow-like coupling-head pivotally connected to a draw-bar by a leaf or joint b, the said coupling-head being provided with means for raising or turning it in a vertical plane, in combination with 65 a coupling-head having laterally-movable jaws for engaging shoulders or projections of first head, substantially as set forth.

2. In a car-coupler, an arrow-like coupling-head pivotally connected to a draw-bar and 70 a coupling-head having laterally-movable jaws for engaging the first head, the said coupling-heads having their draw-bars or inward portions mounted or supported in brackets which carry buffers beneath the coupling 75 parts, substantially as set forth.

3. In a car-coupler, an arrow-like head X and a head Y having double hooks or jaws, in combination with a movable keeper provided with means for preventing an up or 80 down disengagement of said heads, substantially as set forth.

4. In a car-coupler, an arrow-headed or wedge-shaped draw-head provided with hooks or shoulders, a double-hooked head adapted 85 to engage the first head, and having a transverse keeper adapted to retain the heads in a coupled position, as set forth.

5. In a car-coupler, an arrow-like coupling-head having its draw-bar supported by a 90 bracket or frame carrying a buffer beneath the coupling part, and a coupling-head having laterally-movable jaws for engaging first head and supported by a bracket or frame carrying a similar buffer, in combination 95 with means for disengaging or uncoupling the heads, substantially as set forth.

In testimony whereof we have hereunto set our hands this 8th day of October, 1896.

ALBERT FROMMANN.
PHILIPP ENCK.
